UNITED STATES PATENT OFFICE.

ARTHUR O. AUSTIN, OF BARBERTON, OHIO.

DESIGN FOR AN INSULATOR.

46,014.

Specification for Design.

Patented June 30, 1914.

Application filed April 18, 1914. Serial No. 832,979. Term of patent 7 years.

To all whom it may concern:

Be it known that I, ARTHUR O. AUSTIN, a citizen of the United States, residing at Barberton, in the county of Summit and State of Ohio, have invented a new, original, and ornamental Design for an Insulator, of which the following is a specification, reference being had to the accompanying drawing, forming a part thereof, and wherein—

Figure 1 is a perspective in one position of an insulator embodying my new design,

Fig. 2 is a perspective of said insulator in another position, and Fig. 3 is a transverse sectional view of said insulator.

I claim:

The ornamental design for an insulator, as shown.

ARTHUR O. AUSTIN.
